STRIP DISPENSING CARTON

Richard H. Bayer, New York, N. Y., assignor to
 Fibre Cord Company, division of Kary-Safe
 Company Inc., New York County, N. Y., a cor-
 poration of New York

Application December 5, 1942, Serial No. 468,177

12 Claims. (Cl. 206—58)

This invention relates to cartons for dispensing strips, ribbons, cords and the like. More particularly, the invention relates to a carton of the character described having means formed from the material thereof for guiding a strip, ribbon or strand withdrawn from the carton and for severing the strand, leaving a portion thereof exposed for convenient gripping to facilitate withdrawal of another length.

The novel features of the invention will be best understood from the following description when taken together with the accompanying drawing, in which certain embodiments of the invention are disclosed, and in which the separate parts are designated by suitable reference characters in each of the views; and in which:

Fig. 1 is a perspective view of a carton made according to my invention with parts of the construction broken away and in section.

Fig. 2 is a longitudinal section on the line 2—2 of Fig. 1.

Fig. 3 is a cross section on the line 3—3 of Fig. 1, and

Fig. 4 is an enlarged view similar to Fig. 2, but showing only a part of the construction, and showing a modification.

The structure disclosed in this application constitutes an improvement on the construction disclosed in the application of Harry J. Rossi, filed December 14, 1939, Serial Number 309,178.

In the Rossi application the ribbon or strand is withdrawn through one wall of the carton adjacent one corner thereof and cut at the opposed corner of the same wall, and as a result, often times the end of the ribbon or strand which was intended to be left protruded from the carton would be withdrawn or would be moved into positions rendering the same non-accessible. Further difficulties have been experienced in severing the strand, particularly by reason of the fact that if the strand was grabbed short and adjacent the cutting member, the fingers of the hand would engage the carton and limit this cutting operation.

With my improved carton, I have cut from the material of the two angularly disposed walls of the carton guide channels for guiding the ribbon or strand as it is withdrawn from the roller, reel or other support within the carton and further I have arranged the severing means at a corner diagonally disposed with respect to the corner of the carton through which the strand is drawn. Furthermore the severing means in the form of a single edge razor blade is supported by means completely formed from the material of the car-

ton, which means further reinforces that part of the carton in connection with which the severing means or blade is supported.

The carton 10 is formed from a single blank of sheet material substantially in accordance with the teachings of the Rossi application herein identified and in the inexpensive uses of the invention the sheet material will be paper board, lithographed cardboard or the like.

For purposes of description, the wall 11 will be referred to as a back wall, and this wall has projecting flanges or flaps 12 and 13 apertured to facilitate mounting of the carton on a wall, table or other support. In hanging on a wall, 15 the flange 12 will be disposed upwardly, thus the wall 14 will be referred to as the top wall, the wall 15 the bottom wall, the wall 16 the front wall, and the walls 17 the side walls.

The rear end portion of the top wall 14 has an inwardly folded flap or flange 18 which is adapted to bear upon or frictionally engage the ribbon, tape or strand 19 as it is pulled through the opening 20 from a spool, reel or other holder 21, arranged within the carton.

At this time it is well to mention that the invention is designed particularly in dispensing ribbon which is wound upon spools similar to the spool 21 and particularly when these spools contain many yards of ribbon and where dispensing will extend over a long period of time.

The ribbon 19 after passing through the opening 20 is passed along the top wall 14 and then inwardly through an elongated aperture 22 formed in the wall 14 and then outwardly through a smaller elongated aperture 23 formed in the front wall 16. The apertures 22 and 23 are produced by cutting the flaps 24 and 25 respectively from the walls 14 and 16, and these flaps may be secured to inner surfaces of the walls as shown or may be simply left free as indicated by the dotted lines in Fig. 2 of the drawing.

The free end of the ribbon 19 will lie upon the outer surface of the front wall 16 to be accessible for grasping by the hand in pulling a predetermined length of the ribbon from the container or carton in the operation of severing the same by pulling the ribbon over the cutting edge of a razor blade 26, supported at the corner of the carton diagonally opposite the outlet corner 20 and formed between the walls 15 and 16.

The razor blade 26 is supported upon the wall 15 by a tab 27 cut out from the wall 16 as indicated by the opening 28. The free end of the tab having laterally extending flanges or ears 55 29 adapted to be passed through spaced apertures

30 formed in the wall 15. The folded portion of the tab 27 and adjacent wall 15 of the carton are cut out as indicated at 31 and these cut out portions form a pair of inturned flanges 32 adapted to engage the enlarged backed side 33 of the razor blade 26 to support the blade against displacement. By properly controlling the width of the cut outs 31 as well as the depth thereof, the positioning of the cutting edge of the blade 26 may be located in the opening 31 which exposes the cutting edge for engagement by the ribbon 19 in the operation of severing the ribbon.

In Figs. 1 and 2, the tab 27 is folded outwardly, thus supporting the blade 26 on the outer surface of the wall 15. However, when the carton is lithographed on one surface only this would expose an unlithographed or unfinished surface of the tab 27. In such instances, it will be preferred to fold the tab 27 inwardly, thus mounting the blade 26 on the inner surface of the wall 15 as is indicated in Fig. 4 of the drawing.

With the present construction it will be apparent that the flange or flap 18 will engage the ribbon 19 to establish sufficient friction to support the withdrawn portion of the ribbon in extended position. The two apertures 22 and 23 also serve to maintain the free end of the ribbon in a more or less centralized position upon the wall 16 for engagement by the fingers of a hand.

The diagonal positioning of the ribbon in passing through the apertures 22, 23 prevents the ribbon from passing over a sharp corner which facilitates free withdrawal of the ribbon, and the length and relative contour of the two apertures also compensates for the travel of the ribbon along the full length of the spool in the operation of unwinding the same, the aperture 22 and the angularity of the end walls thereof being such as to take in the full length of the discharge opening 20. This construction tends to eliminate binding of ribbon as might otherwise be experienced.

In actual use the cartons in their flat, knock-down condition may be shipped with a number of spools and the assemblage made by the distributor or user. The blade assemblage with the wall 15 may be made while the carton is in its knockdown state and in either of the positions disclosed.

It will also be understood that in the operation of withdrawing the ribbon from the carton, the ribbon may be pulled in a line substantially straight with the two apertures 22, 23, but when the ribbon is being severed, the further bending of the ribbon at the corner portion where the blade 26 is located tends to more securely hold the ribbon against slippage from the spool, thus insuring a positive severance of the ribbon.

Having fully described my invention, what I claim as new and desire to secure by Letters Patent is:

1. A device for dispensing ribbon and similar strands, said device comprising a substantially rectangular container in which the strand to be dispensed is adapted to be arranged, one edge portion of the container having an elongated discharge opening, means at a diagonally opposed edge of the container for supporting a cutter for severing the strand withdrawn from the container, and an intermediate edge portion of the container having on angularly extending walls registering apertures through which the strand passes to centralize the free end portion of the strand on one of said last named walls.

2. A device for dispensing ribbon and similar

strands, said device comprising a substantially rectangular container in which the strand to be dispensed is adapted to be arranged, one edge portion of the container having an elongated discharge opening, means at a diagonally opposed edge of the container for supporting a cutter for severing the strand withdrawn from the container, an intermediate edge portion of the container having on angularly extending walls registering apertures through which the strand passes to centralize the free end portion of the strand on one of said last named walls, and said first named means comprising a tab cut from the material of one wall of the container and secured to the adjacent portion of another wall thereof.

3. A device for dispensing ribbon and similar strands, said device comprising a substantially rectangular container in which the strand to be dispensed is adapted to be arranged, one edge portion of the container having an elongated discharge opening, means at a diagonally opposed edge of the container for supporting a cutter for severing the strand withdrawn from the container, an intermediate edge portion of the container having on angularly extending walls registering apertures through which the strand passes to centralize the free end portion of the strand on one of said last named walls, said first named means comprising a tab cut from the material of one wall of the container and secured to the adjacent portion of another wall thereof.

4. A device for dispensing ribbon and similar strands, said device comprising a substantially rectangular container in which the strand to be dispensed is adapted to be arranged, one edge portion of the container having an elongated discharge opening, means at a diagonally opposed edge of the container for supporting a cutter for severing the strand withdrawn from the container, an intermediate edge portion of the container having on angularly extending walls registering apertures through which the strand passes to centralize the free end portion of the strand on one of said last named walls, said first named means comprising a tab cut from the material of one wall of the container and secured to the adjacent portion of another wall thereof, and said tab and last named wall being cut out to form an opening exposing the cutter there-through.

5. A device for dispensing ribbon and similar strands, said device comprising a substantially rectangular container in which the strand to be dispensed is adapted to be arranged, one edge portion of the container having an elongated discharge opening, means at a diagonally opposed edge of the container for supporting a cutter for severing the strand withdrawn from the container, an intermediate edge portion of the container having on angularly extending walls registering apertures through which the strand passes to centralize the free end portion of the strand on one of said last named walls, said first named means comprising a tab cut from the material of one wall of the container and secured to the adjacent portion of another wall thereof, said tab and last named wall being cut out to form an opening exposing the cutter there-through, and said last named cut out forming two tabs adapted to engage a cutter to aid in supporting the same in position.

5. A strand dispensing device, comprising a container formed from a single sheet of material folded to form when assembled a rectangular body having front, back, top, bottom, and side walls, means extending longitudinally of the edge portion of the container, formed between the back and top walls, for guiding and supporting a strand withdrawn from the container, means centrally of the edge portion, formed between the front and bottom walls of the container, for supporting a cutter, means integral with the back wall for securing the container to a suitable support, and said cutter supporting means comprising a tab cut from the material of one wall of the container and secured to an adjacent wall thereof.

6. A strand dispensing device, comprising a container formed from a single sheet of material folded to form when assembled a rectangular body having front, back, top, bottom, and side

walls, means extending longitudinally of the edge portion of the container, formed between the back and top walls, for guiding and supporting a strand withdrawn from the container, means centrally of the edge portion, formed between the front and bottom walls of the container, for supporting a cutter, means integral with the back wall for securing the container to a suitable support, said cutter supporting means comprising a tab cut from the material of one wall of the container and secured to an adjacent wall thereof, and said top wall and front wall having elongated apertures centrally thereof adjacent the top front edge of the container for guiding the strand withdrawn from the container and centralizing the same on the front wall thereof.

7. In a strand dispenser comprising a container through which a strand is withdrawn longitudinally of one edge portion of the container and between two angularly disposed walls thereof, means at an opposed edge of the container and between two other angularly disposed walls thereof for supporting a cutter employed to sever the strand withdrawn from the container, said means comprising a tab secured to one of said last named walls, and said tab and last named wall being cut out to expose the edge of the cutter at said edge portion.

8. In a strand dispenser comprising a container through which a strand is withdrawn longitudinally of one edge portion of the container and between two angularly disposed walls thereof, means at an opposed edge of the container and between two other angularly disposed walls thereof for supporting a cutter employed to sever the strand withdrawn from the container, said means comprising a tab cut from one of said last named walls and foldable onto the other of said last named walls and secured thereto, and the tab and last named wall being cut out to form an opening exposing a cutter therethrough at said last named edge of the container.

9. In a strand dispenser comprising a container through which a strand is withdrawn longitudinally of one edge portion of the container and between two angularly disposed walls thereof, means at an opposed edge of the container and between two other angularly disposed walls thereof for supporting a cutter employed to sever the strand withdrawn from the container, said means comprising a tab cut from one of said last named walls and foldable onto the other

of said last named walls and secured thereto, the tab and last named wall being cut out to form an opening exposing a cutter therethrough at said last named edge of the container, the cutter comprising a single edge razor blade, and means on the last named wall and said tab engaging the blade to retain the same against displacement.

10. In a strand dispenser comprising a container through which a strand is withdrawn longitudinally of one edge portion of the container and between two angularly disposed walls thereof, means at an opposed edge of the container and between two other angularly disposed walls thereof for supporting a cutter employed to sever the strand withdrawn from the container, said means comprising a tab cut from one of said last named walls and foldable onto the other of said last named walls and secured thereto, the tab and last named wall being cut out to form an opening exposing a cutter therethrough at said last named edge of the container, the cutter comprising a single edge razor blade, means on the last named wall and said tab engaging the blade to retain the same against displacement, one of the last mentioned angularly arranged walls and one of the first mentioned angularly arranged walls having registering apertures for guiding the strand at a point intermediate the two opposed edge portions of the container.

11. The combination with a ribbon dispensing carton, of means at one edge portion of the carton for severing ribbon withdrawn from the carton, said means comprising a razor blade arranged flat upon one wall of the carton to expose one edge portion of the blade longitudinally of one edge defined by said wall, and means independent of said blade and secured to said wall for supporting the blade against displacement therefrom.

12. The combination with a ribbon dispensing carton, of means at one edge portion of the carton for severing ribbon withdrawn from the carton, said means comprising a razor blade arranged flatly upon one wall of the carton to expose one edge portion of the blade longitudinally of one edge defined by said wall, means secured to said wall for supporting the blade against displacement therefrom, and said last named means comprising a tab formed integrally from an adjacent angularly disposed wall of the container.

RICHARD H. BAYER.
